DELAYED ACTION EXPLOSIVE MUNITION

Leon M. Prince, Jr., New York, N. Y., and Louis G. Willke, United States Army, Edgewood Arsenal, Md., assignors to the United States of America as represented by the Secretary of War

Application August 15, 1944, Serial No. 549,602

3 Claims. (Cl. 102—6)

(Granted under Title 35, U. S. Code (1952),
sec. 266)

1

The invention described herein may be manufactured and used by or for the Government, for governmental purposes without the payment to us of any royalty thereon.

This invention relates to munitions and particularly to bombs having a delayed action burster or fragmentation unit.

Munitions with which this invention is particularly concerned are incendiary aircraft bombs of the intensive type, e. g., thermit filled bombs for causing disruption of military importance. This type of bomb is intended to cause a conflagration by a concentrated high temperature burning as a unit until consumed.

Explosive incendiary bombs were developed to discourage fire fighting action. At first, explosive incendiaries were made by incorporating a small burster charge of black powder into the noses of the bombs to have an explosion occur when the incendiary charges burned down. These bombs failed to give more than a small explosion, just a puff, and resulted only in harassing or frightening fire fighters. Later, attempts were made to use high explosives as burster charges, but difficulties were encountered in obtaining satisfactory tactical results, since without proper delay action the high explosive, in functioning too soon after impact, scatters the incendiary filling before incendiary action occurs, reveals the location of the incendiaries, and fails to act as a delayed restraint against fire fighting efforts. Similarly, if the explosion is consistently delayed to the end of the burning of the incendiary, the surprise factor is reduced. A common difficulty in designing explosive incendiaries has been in using high explosive charge in standardized incendiary bombs with positive but variable delayed detonation after impact on target surfaces of various degrees of hardness, e. g., on the ground or on concrete.

To obtain improved explosive incendiary bombs which avoid previous difficulties, this invention has among other objects those of providing incendiary bombs with high explosive bursters without necessitating any substantial changes in the appearance, weight or ballistics of the bombs. It is concerned with providing the bombs with a fragmentation burster having a high explosive charge of lethal proportions in combination with a detonating means which is effective for varying the time of detonation of the high explosive after the impact of the bomb for a period from a fraction of a minute to several minutes. Further, it has the object of proportioning and constructing the burster unit in

2

such a manner that the high explosive is satisfactorily protected against premature ignition or decomposition by high temperature heat generated in the bomb before such heat effects the functioning of the detonator so that the explosion is made to occur through the functioning of the detonator. It has the additional object of providing an explosive bomb constructed so as not to interfere with the assembling, loading, handling, clustering, aiming, and functioning of the bombs.

The foregoing and further objects of the invention will be understood from the following detailed description in conjunction with the accompanying drawings and claims.

Without being limited thereto, the invention is described with reference to several practical embodiments illustrated in the accompanying drawing, in which:

- 20 Figure 1 is a longitudinal sectional view of one type of incendiary bomb with a delayed action explosive unit.
- Fig. 2 is an elevational view of the tail end of the bomb on a larger scale;
- 25 Fig. 3 is a cross sectional view taken on line 3—3 of Fig. 1 on a larger scale;
- Fig. 4 is an elevational view of the nose end of the bomb shown in Fig. 1 on a larger scale;
- 30 Fig. 5 is a longitudinal sectional view of a nose end portion of another type of explosive incendiary bomb;
- Fig. 6 is a longitudinal sectional view of a nose end portion of a 3rd type of an explosive incendiary bomb;
- 35 Fig. 7 is a longitudinal sectional view of a 4th type of delayed action explosive incendiary bomb;

Fig. 8 is a cross-sectional view of a truncated cone delay element which may be alternately used in place of a disc or other shape of delay element interposed between a thermit filling and the top end of a live detonator in a burster.

It will be understood from the following description that this invention is concerned with the utilization of various shapes, sizes and kinds of metal delay elements for influencing the time required for transmission of heat from a burning incendiary agent in a bomb in sufficient intensity to activate a suitable heat-sensitive detonator and, in turn, a high explosive burster charge in predetermined time ranges.

The military requirements for an explosive incendiary bomb are:

- (1) Smallest possible change in construction and appearance;

(2) Positive functioning of the explosive charge under all climatic conditions and with different kinds of impact;

(3) Variable delay in explosion from a few seconds to about 10 minutes after impact; and

(4) Capability of producing casualties and damage over a substantial area.

In general, the assembly of the burster, detonator, and delay elements is to be located in a munition where heat can be conducted at a suitable rate from a burning charge in the munition through the delay element to the detonator. With explosive incendiary bombs of the thermit-type, the practice is to place this assembly at the nose end of the bombs. It is desirable to fill the bomb casing with a thermit-type incendiary agent, commonly known as thermit, pressed in from the top of the casing and to insert the burster and detonator from the nose end following the thermit loading.

Referring particularly to Fig. 1 of the drawings, an explosive, incendiary bomb forming one embodiment of this invention comprises a body 5, made of cast magnesium or magnesium alloy, hexagonally shaped, and filled with a thermit charge 6. A cast iron or steel nose 7, mortised into the nose (lower) end of body 5 serves as a burster case and also serves to make the bomb plummet with suitable velocity in an upright position when dropped from aircraft.

A first fire charge 8 is loaded through the tail (upper) end of body 5. The first fire charge 8 is pressed into a truncated conical projection 9 to fill a corresponding shaped recess at the end of thermit charge 6. A small depression 10 is formed in the center of the exposed surface of the first fire charge 8 to aid ignition thereof.

The first fire charge 8 is formulated to be readily ignited by a standard type of primer cap 11, spaced therefrom and held in a primer cap holder 12 of steel or aluminum which seats against the shoulder 13 formed in the body casting 5.

The primer cap is adapted to be fired by a firing pin 14 disposed in a firing pin holder 15. The firing pin 14 may be made of aluminum or steel and includes a weight portion 16. The firing pin weight portion 16 has a projection 18 of reduced diameter adapted to set within a turned-in flange 19 of the firing pin holder 15. The firing pin 14 is normally retained in the position shown by means of a screw 20 and a cross-shaped brace member 21. The cross-shaped member 21 is made of brass or other deformable materials, so that upon a predetermined impact of the bomb, the crossed strips of this member will fold up and permit the firing pin 14 to slide toward the primer cap 11.

The firing pin assembly is held in place by screws 22. A safety pin 23 is provided with a spring 24 fitting therearound to tend to force the safety pin 23 in a withdrawn or armed position. This type of bomb is adapted to be loaded into clusters so that a number of bombs, for example, 50 or more, fit against one another to press the safety pins 23, into an unarmed position, wherein the safety pins 23 pushed under the firing pins 14 prevent accidental movement of the firing pins toward the primer caps 11.

A hexagonally shaped tail 25 is attached to the tail (upper) end of the body 5 and is held in place by the screws 22. The tail 25 stabilizes the downward flight of the bomb. Vent holes or openings 26 are formed in the body casting 5 between the primer cap holder 12 and the first

fire charge 8. The outer ends of the holes 26 are counterbored so as to receive plugs or stoppers 27, which may be made of rubber, fibre board or metal cups, which are blown out by gases evolved from the burning charge. In order to make the bomb waterproof, the outer surfaces of the plugs 27 are coated with a waterproof cement or lacquer, preferably, the inner surfaces of the holes 26 are also lacquered before the insertion of the plugs 27. One practical form of the bomb illustrated in Fig. 1, which has been standardized, has a total weight of about four lbs. and an overall length of about 21 $\frac{1}{4}$ inches. The magnesium alloy casting 5 has a weight of about 1 lb. 4 oz., a length of about 11 $\frac{1}{2}$ inches and for the greater part of its length, has a thickness of about $\frac{1}{2}$ ".

A suitable thermit mixture for forming the core charge 6 has the following composition in percentage by weight:

	Per cent
Aluminum, granular	15.7 to 16.3
Iron oxide scale or iron ore	43.5 to 44.5
Aluminum, grained	8.8 to 9.2
Barium nitrate	28.6 to 29.4
Sulfur	1.9 to 2.1

The weight of the charge 6 in a bomb weighing about 4 lbs. is about 265 grams. The thermite charge 6 is preferably loaded into the body 5 in four approximately equal increments under a dead load pressure of 6,000 to 7,000 lbs. using a ram shaped to form a truncated conical depression corresponding to the shape of the truncated projection 9 of the first fire charge 8.

The first fire charge 8 for a 265 gram thermit charge should weigh about 19 to 21 grams and may be pressed on top the charge 6 under a dead load of 6000 to 7000 lbs. using a ram shaped to form a rounded depression 10. A suitable first fire charge composition comprises 25% magnesium powder and 75% barium chromate.

Next, referring more particularly to the nose end assembly shown in Fig. 1, the steel or iron nose cup 7 is mortised into the nose end of the body 5, and has integral parts 28 and 29 of reduced cross-section at its inner end. The nose cup 7 has a relatively large hollow chamber 30 for containing a suitable high explosive. At its front end opening, the nose cup 7 is threaded to receive a closure plug 31 provided with drill holes 32 for receiving a spanner wrench in tightening the plug into position. A fibrous or felt pad 33 is placed adjacent the plug 31 in closing the explosion chamber after it has been loaded with high explosive and with a detonator tube 34 inserted into a central bore 35 through the reduced cross section extension 29. A metal or plastic disc 36 may be placed in the explosion chamber 30 at the base of the detonator tube 34 to offer resistance to the movement of the detonator tube when the bomb is subjected to impact.

A delay element disc 37 is interposed at the end of the nose cup extension 29 between the thermite filling 6 and the open inner end of the detonator tube 34. The material, shape and size of this disc 37 is a factor in determining the delay period for transmission of heat from the burning part of the bomb to the detonator for initiating detonation of the high explosive in chamber 30.

In a bomb having substantially the construction illustrated in Fig. 1 a steel disc approximately 0.960" in diameter and 0.06" thick may be dropped into the body from the tail end prior to loading of the body with thermit and first fire

charge. Following the loading with the nose cup 7 in position, the detonator 34 may then be inserted through the open end with plug 31 removed until the open end of the detonator tube contacts with the underside of the steel disc 37.

With a suitable detonator tube thus in place, and a suitable high explosive, such as tetrinitromethyliamine, filling the explosion chamber 30, the nose cup is closed by screwing in the threaded plug 31.

In a bombing operation, when a cluster of the bombs is released from aircraft, bands which hold the bombs in the clusters are broken so as to permit the individual bombs to fall separately in a pattern toward the target. As the bombs separate from one another, the safety pins 23 which were pressed inwardly in the cluster are released to the position shown in Fig. 3 so as to arm the bombs. Upon impact of the nose end of a bomb, the inertia movement of the weight portion 16 of the firing pin 14 acts to deform the retaining cross shaped member 21 so as to allow the firing pin 14 to strike the primer cap 11. The primer cap 11 flashes into the depression 10 of the first fire charge 8, thereby igniting this charge. The gases produced by the combustion of the ignited first fire charge 8 develop sufficient pressure to blow out the vent hole plug 27, thus leaving a passage for escape of combustion gases evolved by the burning incendiary charge so as to prevent explosion of the incendiary unit before the delayed explosive unit functions.

The first fire charge 8 burns at a temperature sufficiently high to ignite the thermate charge 6, which in turn ignites the adjacent body 5 of the bomb where an intense incendiary action is obtained. A portion of the heat tends to flow through the bomb body toward the nose end where the burster unit is located. The intensity of the heat which reaches the burster unit depends on the proximity of the burning portion of the incendiary charge 6, the burning advancing gradually toward the nose end of the bomb.

When bombs assembled as described were tested by static firing, delays from about 1 minute up to 12 minutes and longer, from the instant the thermate began to burn until the explosion, were obtained. On dropping these bombs from a plane at 1,000 feet and 4,300 feet onto concrete, the average delays were even longer on account of the tendency of the detonator to be set back a short distance from the steel disc 37 and, accordingly, the variable delay range was somewhat increased but without misfires of the explosive.

Statically fired, the average delay was about 1 minute 45 seconds, and on dropping onto concrete the average delay was approximately 2 minutes 30 seconds measured from the instant of impact till the explosion. A rough approximation of the percentages of explosions in varied delay ranges were: 10% in 1 to 2 minutes; 50% in 2 to 3 minutes; 25% in 3 to 4 minutes; 10% in 4 to 5 minutes; and 5% in 5 to 12 minutes.

Thus, it was determined that a very satisfactory variation in delay is obtainable with substantially no failures in explosion.

Investigation shows that a number of readily available high explosives could be used satisfactorily in the nose cup. Tetryl was generally satisfactory. Trinitrotoluene, particularly in pellet form, Tetrytol and Hexalite gave good results even though they were at first suspected of being too sensitive to thermal decomposition for such a use and the chamber 30 may be charged with

one or more of these explosives instead of tetryl. It is thus indicated that construction with suitable delay elements and a proper detonator serves to preserve the high explosive until the detonation action is initiated in the detonator through delayed heat transmission thereto, even after the incendiary agent in the bomb has been consumed.

The detonator tube 34, in general, comprises a slow burning train of non-explosive powder leading to a primer and a booster explosive enclosed in a flexible metallic jacket. A detonator of this type has an aluminum or copper gilding-metal jacket 38, 0.274 inch O. D., open at the top where the delay train is exposed and closed at the bottom. The delay train powder 39 comprising preferably a readily reducible metal oxide, and a readily oxidizable element is compressed in a lead tubing 40 staked tightly within the jacket 38. At the open end of the jacket 38, the delay powder is extruded flush with the top of the jacket. A delay powder comprising barium peroxide and silicon ignites at approximately 300° C. and undergoes practically gasless auto combustion, at a rate of approximately 5 seconds per inch, thus burning from end to end in about 1 to 3 seconds. This delay train terminates in an ignition charge 41 of a 70-30 mixture of lead ortho-cresol and potassium chlorate, diazo-dinitrophenol, or the like. Three grains of this charge 41 pressed at 200 lbs, ignites at about 270° C. The ignition charge is pressed against a primer charge 42 comprising lead azide, or the like, disposed next to a bottom booster charge 43 made up of 14 grains of tetryl, preferably phlegmatized.

Following the principles set forth, the detonator may have varied ingredients. This type of detonator occupies a very small space. It is satisfactorily stable against shock and against changes by varied climatic conditions. The thin flexible metal container or jacket is subject to some deformation on impact of the bomb, but this deformation does not interfere with the functioning of the detonator but rather tends to increase the delay in the action of the detonator.

In the type of bomb having a nose as illustrated in Fig. 5, the detonator tube 134 inserted in the neck or extension 29 of the steel nose 7 has a flanged top 44 which serves to hold the detonator tube 134 in position against the metallic delay element 137. In place of a steel disc, a magnesium disc about 0.064" thick may act as the partitioning delay element 137. The magnesium disc acts to protect the detonator while the thermate is being loaded. When the thermate nearly burns down to this magnesium disc, the magnesium disc burns quickly and promptly initiates the burning of the delay powder train in the detonator 134. The desirability of this action lies in the fact that this bomb may be mistaken as a long delay bomb and those who attempt to extinguish the bomb before a delayed explosion will be injured or killed. In actual tests, 75% of the explosions occurred in 60 to 70 seconds after impact, and the remaining 25% before 4 minutes.

In the type of bomb nose assembly illustrated in Fig. 6, the metallic delay element 237 is cast integral with the bomb body 5. The detonator tube 234 is inserted into a hole drilled into the partitioning member 237 which is cast integral with the body 5, but a $\frac{1}{8}$ " thickness of magnesium separates the top of the detonator from

the thermite, and this thickness of magnesium acts in the same way as 0.06" steel disc. It prevents flame from reaching the detonator and serves to delay the flow of heat to the detonator. Several perforated discs 46 of high melting point plastic, such as phenol-formaldehyde resin, may be disposed to collar the detonator tube 34 to serve as an insulation and guide for further protection of the detonator and the high explosive in this type of construction.

By forming the integral delay partition member 337 in the shape of a truncated cone, as shown in Fig. 7, the delay period may be shortened more uniformly, for when the thermit surrounding the cone begins to burn, the cone is readily ignited and thereupon heat is quickly transferred to the detonator tube 234. However, a separate conical disc element 437 (see Fig. 8) may be used instead of an integral partition member should a shorter delay be desired. Bombs with the conical delay element produced 85% of the explosions 35 to 60 seconds after impact and the remaining 15% of explosions were distributed from 1 to 3 minute intervals after impact.

Theoretical principles which may be considered as involved in the functioning of the heat transmitting delay elements are:

(1) The delay elements serving to protect the detonator from the flame and heat generated by the burning thermite for a period after impact are capable of conducting heat of sufficient intensity to initiate the action of the detonator before heat conducted to the nose cup can affect the high explosive therein;

(2) The delay in heat transmission to the explosive in the nose cup and to the charge in the detonator is a function of the distance that the heat must travel to reach these charges.

A favorable characteristic of the detonator is that it permits the high explosive charge to be kept intact until fired by detonation. In the delayed action detonating means described, there are no moving parts and its elements are not fractured under the strains and shocks imposed upon impact of the high velocity bomb. The types of delay means used eliminate the need of any pyrotechnic delays which are susceptible to damaging by the shock incurred, and which must be provided with elongated connecting links which require excessive space and work in assembling. The delay elements used in the present invention are simple and ideally suited for large scale production with a minimum chance for difficulties.

It is to be understood that the invention is not

to be limited by the forms of embodiments described nor by any theory of mechanism of their operation, but that modifications come within the spirit and scope thereof.

5 We claim:

1. A bomb including a casing, a recessed nose portion mortised into the front end of the casing, said nose portion containing a high explosive charge in its front end portion and an elongated detonator tube to the rear of said charge, said casing containing a slidably mounted firing pin, a primer cap holder spaced apart from and in front of said firing pin, a first firing charge spaced apart from and in front of said firing pin, a primer cap holder, a thermit charge in front of said firing charge, said first firing charge, and said thermit charge being highly compacted together after being loaded in the casing, said detonator tube being open at its rear end portion and having an ignition charge in its front end portion and a delay powder train for igniting said ignition charge.

2. The bomb of claim 1 in which the rear end portion of the first firing charge is recessed and its front end portion is rammed into a recess in the rear end portion of said thermit charge.

3. The bomb of claim 1 in which the firing charge consists of an admixture of magnesium powder and barium chromate and the thermit charge consists essentially of a highly compacted admixture of sulphur, grained aluminum, granular aluminum, barium nitrate and a compound of iron and oxygen.
